(57) **CLAIM**

The ornamental design for a map holder with fold-out map, as shown and described.

DESCRIPTION

FIG. 1 is a front elevational view of the first preferred embodiment of the map holder with fold-out map shown in the closed position.

FIG. 2 is both the right and left edge view thereof.

FIG. 3 is the rear view thereof.

FIG. 4 is a top view thereof.

FIG. 5 is a bottom view thereof.

FIG. 6 is a view of the map holder in the open position with the fold-out map in the folded position.

FIG. 7 is the same as FIG. 6 showing the map in the unfolded position.

FIG. 8 is a front elevational view of the second preferred embodiment of the map holder with fold-out map of this invention shown in the closed position.

FIG. 9 is a left and right side edge view thereof.

FIG. 10 is a rear view thereof.

FIG. 11 is a top view thereof.

FIG. 12 is a bottom view thereof.

FIG. 13 is a front elevational view thereof with the map holder in the open position and the map in the folded position; and, FIG. 14 is similar to FIG. 13 and shows the map in the unfolded position.
